UNITED STATES PATENT OFFICE.

FRANK BERNARDI, OF STOCKTON, CALIFORNIA, ASSIGNOR TO PATENT ELECTRIC FUSE SPITTER CO., OF MOKELUMNE HILL, CALIFORNIA, A CORPORATION OF CALIFORNIA.

FUSE SPITTER.

1,218,512.

Specification of Letters Patent.

Patented Mar. 6, 1917.

Application filed April 17, 1916. Serial No. 91,833.

To all whom it may concern:

Be it known that I, FRANK BERNARDI, a citizen of the United States, residing at Stockton, in the county of San Joaquin and 5 State of California, have invented new and useful Improvements in Fuse-Splitters, of which the following is a specification.

This invention relates to a fuse spitter, and particularly to an improvement on my 10 former patent, No. 913,566, of February 23, 1909, entitled "Electrical fuse spitter".

For the purpose of igniting the explosive charges used in mining or blasting operations, it is common practice to connect the 15 charge with one end of a powder fuse which is electrically or otherwise ignited at the opposite end. It sometimes happens that careless handling of the fuse causes so much powder to fall out of the end of the fuse 20 that the interval of time allotted for burning is reduced, and also that the final spitting action will not have sufficient flash or force to ignite the charge, thereby causing either an overlapping of shots or a misfire with connected dangers, etc.

The object of the present invention is to provide means for preventing any powder from falling out of the spitting end of the fuse and also to provide a means for 30 intensifying the flashing or spitting force of the fuse.

Further objects will hereinafter appear.

The invention consists of the parts and the construction and combination of parts 35 as hereinafter more fully described and claimed, having reference to the accompanying drawings in which—

Figure 1 is a side elevation showing the application of the invention to the end of 40 an electrical fuse spitter.

Fig. 2 is an enlarged, longitudinal section of the end of the fuse.

Referring to the drawings in detail, A indicates a section of an ordinary black 45 powdered fuse; 2 a metal cap attached thereto which is connected by means of the wires 3 with a source of electric current supply not here shown. Mounted interiorly of the cap 2 is a pair of terminal members with 50 which the wires 3 connect and a priming charge of powder which connects with the powder train interior of the fuse A. The construction of the cap, together with the electrical connections and manner of attaching same to the fuse does not form any part 55 of the present invention as it is fully illus-

trated in my former patent, No. 913,566, entitled "Electrical fuse spitter" issued February 23, 1909. Electrical fuse splitters of the character shown are generally used 60 for the purpose of igniting black powder or dynamite charges employed in connection with mining and blasting operations and it often happens that the careless handling of the fuse end permits so much 65 of the powder in the spitting end of the fuse to fall out that the time of burning is reduced and often the final spitting action is entirely lost or the flashing force is so weakened that ignition of the explosive 70 powder or dynamite charge is prevented, thus causing a wrong timing or a misfire, which not only causes considerable loss of time but often proves dangerous as they sometimes accidentally ignite while the 75 charge is being removed.

The object of the present invention is to overcome any chance of misfire with the dangers connected therewith by providing means for preventing any loss of powder 80 from the end of the fuse and also by intensifying the spitting action. This is all accomplished by placing a hardened combustible or explosive closing element at the end of the fuse such as indicated at 4. The closing element is formed with a stopper to fit 85 into the end of the fuse and a cap adapted to fit over the end of the fuse, the exterior of the cap being rounded or semi-spherical. The enlargement of the cap with relation to 90 the bore of the fuse which contains the loose powder, increases the explosive volume of the end of the fuse and the semi-spherical surface of the cap provides the maximum explosive surface from which the explosion 95 of the fuse takes place. The closing element may be molded and the stopper forced into the end of the fuse until the cap engages the end thereof or may be formed by dipping the 100 end of the fuse into black powder which has been reduced to a liquid state. The black powder thus covers the end of the fuse and when hardened forms a closure or powder cap, which not only prevents the loss of powder from the fuse but also increases 105 the charge of powder at the end of the fuse to such an extent that the spitting force of the fuse is considerably intensified. For the purpose of protecting the explosive stopper 4 and the fuse proper from moisture and 110 also to protect it against accidental breakage or removal from the end of the fuse, it

has been found advantageous to dip the fuse in paraffin or like material to form a waterproof coating or covering such as indicated at 5.

5 While the fuse plug and intensifier is here shown as used in connection with an electrical fuse spitter, it is obvious that it may be applied to the end of any ordinary fuse. I also wish it understood that the spitting 10 end of the fuse may be capped or plugged with any other explosive material suitable for the purpose.

The materials and finish of the several parts of the invention may be such as the 15 judgment and experience of the manufacturer may dictate.

I wish it understood that various changes in form, proportions and minor details of 20 construction may be resorted to within the scope of the appended claims and that I do not wish to limit myself to the specific design and construction here shown.

Having thus described my invention, what 25 I claim and desire to secure by Letters Patent is—

1. As an article of manufacture, a fuse having a recess, a powder filling in said recess, and an intensifying explosive member comprising a stopper fitting in said recess and having an enlarged outer end forming a cap for the fuse.

2. As an article of manufacture, a fuse having a recess, a powder filling in said recess, and a hardened intensifying explosive 35 member comprising a stopper portion fitting in said recess and having an enlarged outer end forming a cap portion for the fuse.

3. As an article of manufacture, a fuse having a recess, a powder filling in said recess, an intensifying explosive member comprising a stopper portion fitting in said recess and having an enlarged outer end form-

ing a cap for the fuse, and means for holding said member in position.

4. As an article of manufacture, a fuse 45 having a recess, a powder filling in said recess, an intensifying explosive member comprising a stopper portion fitting in said recess and having an enlarged outer end forming a cap for the fuse, and a waterproof 50 covering for holding said member in position.

5. As an article of manufacture, a fuse having a recess, a powder filling in said recess, and an explosion intensifying member 55 having a diameter greater than that of the recess to extend across the end thereof and form a closure for the recess.

6. As an article of manufacture, a fuse 60 having a recess, a powder filling in said recess, an intensifying explosive member having a diameter greater than that of the recess to extend across the end thereof and form a closure therefor, and a protective covering for holding said member in position.

7. As an article of manufacture, a fuse having a recess, a powder filling in said recess, and an explosion intensifying member 70 for the end of the fuse comprising a stopper portion and a cap portion.

8. As an article of manufacture, a fuse having a recess, powder loosely filling said recess, and a relatively compact intensifying 75 member for the end of the fuse comprising a stopper portion and a cap portion.

In testimony whereof I have hereunto set my hand in the presence of two subscribing witnesses.

FRANK BERNARDI.
